UNITED STATES PATENT OFFICE.

HARRY A. DAVIS, OF HOPEDALE, MASSACHUSETTS, ASSIGNOR TO DRAPER CORPORATION, OF HOPEDALE, MASSACHUSETTS, A CORPORATION OF MAINE.

PICKER-STICK MOTION FOR LOOMS.

Application filed April 16, 1925. Serial No. 23,699.

This invention relates to a picker stick motion for a loom of that type in which a picker stick includes at its lower end a rocker shoe mounted to rock upon a rocker support carried by the lay rock shaft and in which the configuration of the surfaces of the rocker shoe and rocker support is such as to maintain the path of movement of the effective end of the picker stick where 5 the picker is located substantially rectilinear and preferably in parallelism with the lay.

The main object of the invention is to provide means for maintaining the rocker shoe throughout its range of movement in 15 contact with the rocker support and thus prevent "jumping" of the picker, whereby the accurate movement of the effective end of the picker stick is secured.

A further object of the invention is to 20 provide a simple and efficient means for angularly adjusting the path of movement of the effective end of the picker stick with respect to the lay.

These and other objects and features of 25 the invention will appear more fully from the accompanying description and drawings and will be particularly pointed out in the claims. As this general type of picker stick motion is well known and familiar 30 to those skilled in the art, it is only necessary to illustrate and describe those parts of the loom directly concerned with the present invention. Furthermore, as the picker stick motion is the same at both sides 35 of the loom, it is sufficient to describe a construction at but one side.

In the drawings:

Fig. 1 is a view in front elevation of the right hand side of a loom showing a preferred form of the present invention embodied therein.

Fig. 2 is a view in vertical cross section taken on the line 2—2 of Fig. 1.

Fig. 3 is a detail in vertical cross section 45 taken on the line 3—3 of Fig. 1.

Fig. 4 is a view similar to Fig. 1 largely in vertical cross section and with the picker stick motion shown at the opposite end of its movement.

50 In a picker stick motion of this type, the lay rock shaft 1, which has its bearing in the loom side 2, has mounted thereon outside of the loom frame a suitable rocker support upon which the rocker shoe 55 of the picker stick is supported and rocks

during the movement of the picker motion. In the preferred form of the present invention, this rocker support comprises a base 3, having a hub 4, fitting over and secured to the end of the lay rock shaft 1. It is 60 desirable, in this type of picker motion known as the "parallel" type, that there be provided some means whereby the path of the effective or upper end of the picker stick may be adjusted into or slightly out 65 of parallel with the surface of the lay so as to give a workable motion in the picking of the shuttle. In the present invention, this is secured by providing as a part of the rocker support a bed plate which is 70 angularly and vertically adjustable on the base or angularly adjustable toward and from the lay so as to produce the desired result. For this purpose a bed plate 5, having a flat top surface, is pivotally mounted 75 at 6 to the outer end of the base 3 and is rigidly and vertically adjustably secured to the base at its inner end. The bed plate is shown as provided with depending side flanges 7 fitting over corresponding depend- 80 ing side flanges 8 of the base. At its inner end, the bed plate is centrally provided with a depending lug 9 which passes down through a slot 10 in the bed plate 3. A transverse shouldered shaft 11 is journaled 85 in the side flanges 8 of the base and has a central eccentric section 12 passing through an elongated slot 13 in the lug 9, and this shaft is provided with a polygonal end 14. A set screw 15 in one of the flanges 8 of 90 the base abuts against the shaft 11. It will thus be seen that by placing a key or wrench on the polygonal end 14 of the shaft 11 and turning this shaft, that the bed plate 5 may be vertically and angularly adjusted 95 on the base as required, and then locked in adjusted position by means of the set screw 15.

In the preferred construction illustrated, the entire picker stick motion is carried 100 by the bed plate portion 5 of the rocker support so that the adjustment of this bed plate effects the desired relation of the path of the effective end of the picker stick with respect to the lay without disturbing in any way the relation of the parts of the picker motion.

The rocker shoe is provided with a shank 16, having a socket in its upper end in which is fitted the lower end of the usual picker 110

stick 17. The picker stick is rigidly secured in this socket by a bolt 18. The base 19 of the rocker shoe is shaped on its lower surface so that as it rocks on the surface of the bed plate 5, the effective end of the picker stick, where the picker is located, will have the required substantially rectilinear movement. The rocker shoe is provided with an extension 20 depending from and passing down through the rocker support. This extension, as is usual, rests against a transverse abutment, shown as a roller 21 mounted on a stud 22, which stud, in the present invention, is preferably mounted in the bed plate.

In the preferred construction illustrated more in detail in Fig. 3, the stud 22 passes transversely through the side flanges 7 of the bed plate, is headed at one end 23 and provided with a nut 24 at the other end. A bearing sleeve 25 fits between the flanges 7 and the stud 22, and the roller 21 is mounted on this bearing sleeve so as to rotate freely. The usual spring 26 is connected at one end to the lower end of the extension 20 and at the other end to some fixed portion of the rocker support, such as the lug 27 on the hub 4. The purpose of these features of the construction is, as usual, to maintain the longitudinal position of the rocker shoe during the picking motion and to return the picker stick at the conclusion of its picking movement.

Considerable difficulty has been experienced in picker motions of this type because of the "jumping" of the picker stick and rocker shoe or the failure of the rocker shoe to remain in contact with the rocker support throughout its range of movement. When this takes place, the required picking movement is interfered with and damage not infrequently caused to the loom.

In the present invention, cooperating means are provided on the picker member, which comprises the picker stick and rocker shoe, and on the rocker support, which in the preferred construction comprises the base and the adjustable bed plate, which cooperating means act positively to prevent lifting of the picker member throughout its range of movement from the path prescribed by the rocker support and the rocker shoe. These cooperating means preferably comprise a transverse guide preferably carried by the depending extension 20 of the rocker shoe, and a downhold cam movably, and preferably pivotally, mounted on the rocker support and moved by the rocker shoe so as to maintain this downhold cam throughout the range of movement of the rocker shoe directly superjacent this transverse guide.

In the preferred construction illustrated, the downward extension 20 of the rocker shoe is slotted vertically or bifurcated and provided at its lower end with a transverse stud 28 on which is mounted a roller 29 be-

tween the bifurcations, and this roller constitutes the transverse guide.

In the preferred construction illustrated also, the downhold cam is mounted on the bed plate 5. For this purpose the bed plate 70 is provided with an upwardly projecting arm 30 curved outwardly at its upper end. This end is slotted or bifurcated and provided with a transverse stud 31. The downhold cam 32 is of sickle shape, so as not to 75 engage the roller 21. This downhold cam is pivotally mounted on the stud 31 and its upper extension 33 is slotted at 34 to engage and slide upon a block 35 which pivots upon the pin 36, transversely mounted in the 80 shank 16 of the rocker shoe. It will thus be seen that as the rocker shoe is moved between the positions shown in Figs. 1 and 4, the downhold cam will be swung upon its pivot 31, due to its sliding engagement with the 85 rocker shoe between the positions illustrated in Figs. 1 and 4. The outer lower surface 37 of the downhold cam is so designed that during this movement it will always be maintained immediately superjacent or in contact with the roller 29 of the transverse guide. Consequently, it is impossible for the rocker shoe to lift off or "jump" from the surface of the rocker support or the bed plate 5 during the entire range of movement 95 of the picker stick.

Not only is the entire construction, in the preferred form of the invention, carried upon the bed plate 5 so as to be angularly adjustable therewith, but the construction is 100 also preferably such as to be symmetrical with respect to the central, vertical plane of movement of the picker stick. Thus it will be seen that the rocker support, including the bed plate 5 and the base 3, is provided with 105 a central, vertical slot in which the depending extension 20 from the rocker shoe and the downhold cam 32 operate, that the depending extension 20 is itself slotted or bifurcated and the downhold cam 32 operates 110 through this slot, that the rocker shoe itself is provided with a central, vertical slot through which the arm 30 from the bed plate 5 of the rocker support projects, that this arm 30 is itself centrally slotted or bifurcated 115 and that the downhold cam is mounted in this slot, that the slot in the rocker shoe extends up through the shank 16 and that the downhold cam 32 swings centrally in this slot. Thus a balanced, symmetrical 120 construction is produced.

Having thus described the invention, what is claimed as new, and desired to be secured by Letters Patent, is:

1. In a picker motion for a loom, a rocker 125 support mounted on the lay rock shaft and presenting a flat top surface, a picker member comprising a picker stick and a rocker shoe mounted to rock on the flat top surface of the rocker support, and cooperating 130

means on the picker member and the rocker support acting positively to prevent lifting of the picker member throughout its range of movement from the path prescribed by the rocker support and the rocker shoe.

2. In a picker motion for a loom, a rocker support comprising a base mounted on the lay rock shaft and a bed plate angularly adjustable on the base toward and from the lay, a picker member comprising a picker stick and a rocker shoe mounted to rock on the bed plate of the rocker support, and cooperating means on the picker member and the bed plate acting positively to prevent lifting of the picker member throughout its range of movement from the path prescribed by the rocker support and the bed plate, whereby the entire mechanism is bodily and angularly adjustable with respect to the base of the rocker support, and consequently to the lay, thereby to adjust the path of movement of the effective end of the picker member.

3. In a picker motion for a loom, a rocker support presenting a base mounted on the lay rock shaft and a bed plate pivoted transversely to the base at one end and means for vertically adjusting the other end of the bed plate on the base, a picker member comprising a picker stick and a rocker shoe mounted to rock on the bed plate of the rocker support, and cooperating means on the picker member and the bed plate acting positively to prevent lifting of the picker member throughout its range of movement from the path prescribed by the rocker support and the bed plate and whereby the entire mechanism supported by the bed plate is bodily and angularly adjustable to adjust the path of movement of the effective end of the picker member.

4. In a picker motion for a loom, a rocker support comprising a base mounted on the lay rock shaft and a bed plate angularly adjustable on the base toward and from the lay, and a picker member comprising a picker stick and a rocker shoe supported by and mounted to rock throughout its range of rocking movement on the bed plate, whereby the entire picker member is bodily and angularly adjustable with the bed plate to adjust the path of movement of the effective end of the picker member.

5. In a picker motion for a loom, a rocker support comprising a base mounted on the lay rock shaft and a bed plate pivoted transversely to the base at one end and means for vertically adjusting the other end of the bed plate on the base and a picker member comprising a picker stick and a rocker shoe supported by and mounted to rock throughout its range of rocking movement on the bed plate, whereby the entire picker member is bodily and angularly adjustable to adjust the path of movement of the effective end of the picker member.

6. A picker motion for a loom having the construction defined in claim 5, in which the means for vertically adjusting the bed plate on the base of the rocker support comprises an eccentric engaging the bed plate and rotarily adjustable in the base.

7. In a picker motion for a loom, a rocker support mounted on the lay rock shaft, a rocker shoe mounted to rock on the rocker support, a depending extension from the rocker shoe having a transverse guide, and a movable downhold cam carried by the rocker support and moved by the rocker shoe to maintain throughout the range of movement of the rocker shoe a position directly superjacent the said guide, thus to prevent the rocker shoe from lifting off the rocker support.

8. A picker motion for a loom having the construction defined in claim 7, in which the downhold cam is pivotally mounted on the rocker support and has a sliding and rocking engagement with the rocker shoe to effect its stated function.

9. In a picker motion for a loom, a rocker support comprising a base mounted on the lay rock shaft and a bed plate vertically and angularly adjustable on the base, a rocker shoe supported by and mounted to rock on the bed plate, a depending extension from the rocker shoe having a transverse guide, and a movable downhold cam carried by the bed plate and moved by the rocker shoe to maintain throughout the movement of the rocker shoe a position directly superjacent to said guide to prevent the rocker shoe from lifting off the bed plate.

10. In a picker motion for a loom, a rocker support mounted on the lay rock shaft and having a central, vertical, longitudinal slot, a rocker shoe mounted to rock on the rocker support and having a central, vertical, longitudinal slot, an arm projecting from the rocker support up through the slot of the rocker shoe, an extension depending from the rocker shoe down through the slot of the rocker support, a transverse guide on the lower end of the extension, and a downhold cam pivoted on the upper end of the arm, slidably connected to the rocker shoe, projecting down through the slots of the rocker shoe and rocker support and maintained during the movement of the rocker shoe directly superjacent the said guide.

11. A picker motion for a loom comprising the construction defined in claim 10, in which the upper end of the arm and the depending extension are both centrally slotted to receive the downhold cam thus to produce a symmetrical construction.

In testimony whereof, I have signed my name to this specification.

HARRY A. DAVIS.
